WELT INSOLE AND METHOD OF MAKING

Elmer A. Ellis, Medford, Mass.

Application November 28, 1942, Serial No. 467,220

2 Claims. (Cl. 12—146)

My present invention is a novel and improved type of insole for use in the manufacture of boots and shoes, and includes a novel method of making such an insole.

My present invention is directed to improve and perfect the construction of a reinforced sewing rib for welt footwear and by a simple and novel process which will enable me to utilize thinner stock for the welt insole blank than has heretofore been possible where channeling has been one of the steps and to form a reinforced channel rib on the inside of the channeled lip portions forming the sewing rib; whereas heretofore such reinforcing has been applied on the outside of the channeled rib.

Many difficulties arose from the former practice of applying "gemying" or reinforcing on the outside of such a sewing rib made by channeling, as it was extremely difficult to insure the sticking of such outer reinforcing to the base of the channeled lip, and during the inseaming operation the sewing machine needles often tended to separate the leather in the rib from the canvas reinforcing on the outside.

By my present invention I eliminate these prior difficulties and insure the reinforcing throughout the entire height of the sewing rib to render same stronger, more sturdy, and insuring proper strength to the rib and inseam stitching, as the entire welt shoe structure depends upon the sewing rib to unite the upper, insole, and welt together in the inseam stitching operation. The importance of the sewing rib will be appreciated.

In carrying out my invention, I am enabled to utilize a blank for the insole of lighter thickness than has heretofore been possible where a channeled insole is formed. This affords a great saving in expense and also renders the resulting shoe structure more flexible because of the thinner insole stock, while my invention insures a strong sewing rib construction.

I apply to the marginal portion of the insole blank, preferably before channeling, a strip of adhesively coated tape which can be easily and quickly applied, following the contour of any insole, and unite the tape and insole blank along the margin, thus giving an increased strength and added thickness on the margin of an insole blank too thin to be channeled for ordinary use, but now with my reinforced tape it can be suitably channeled both with an inner channel and an outer channel, which channels are ordinarily turned up into a composite sewing rib and united by adhesive.

With my reinforced tape, which also has an adhesive coating on the top, and which adhesive may be applied either before or after the channeling, the folded surface of the tape sticks together during the lip-turning operation, thus forming a laminated rib structure composed of two folds of the tape on the inside together with the channeled leather sections on the outside.

In order to insure the reinforcing tape extending throughout the entire height of the sewing rib, I may indent the marginal portion of the insole on a line between the two channeled cuts to be made or I may groove the same and force the tape when applying it into such groove; and thereafter, when the two opposite portions to constitute the sewing rib are turned upwardly into adhesively united relation, the tape will extend as far as, or even below, the depth of the channel cuts.

My reinforced sewing rib structure is intended to be utilized without gemying, although gemying or further reinforcing can be applied if desired. My resultant insole thus utilizes a thin, inexpensive blank for the insole material, which will be much more economical and of much greater flexibility than where an insole blank of sufficient weight or irons to be channeled under ordinary procedure is employed, and thus saves not only costs in leather but also costs in gemying, the sewing rib being itself reinforced by the tape.

I believe that my invention of first reinforcing the marginal part of a blank intended for manufacture into a welt insole, which blank would be normally too thin for such use, and also I consider that the reinforced textile material on the inside of a channeled sewing rib instead of on the outside, are distinct novelties in this art, and I wish to claim each of these features broadly.

It is also within the scope of my present invention to stitch the tape to the marginal portion of the insole with the cemented surface uppermost and then turn up the two layers of tape thus stitched, uniting them into a rib structure independently of channeling.

Referring to the drawing illustrating preferred embodiments of the invention, showing different forms of my improved welt insole and process of making same:

Fig. 1 is a plan view of the insole;

Fig. 2 is a plan view showing progressively the method of applying the reinforcing either before or after channeling and with the lip-turning partially performed;

Fig. 3 is a cross-sectional view on the line 3—3 of Fig. 2;

Fig. 4 is a fragmentary view showing a narrow reinforcing tape and the lip-turning partially performed;

Fig. 5 is a cross-sectional view on the line 5—5 of Fig. 4;

Fig. 6 is a cross-sectional view on the line 6—6 of Fig. 4 extending clear across the insole, and

Fig. 7 illustrates in cross-section a completed insole of Fig. 3 with the optional gemming added.

Fig. 8 is a fragmentary view illustrating a strip reinforcing instead of gemming.

Referring to the drawing, an insole blank 1 is shown of suitable contour and size desired, which may be formed of extremely thin channelable stock, preferably leather, of as thin a stock as two irons. Thus, I may utilize leather "splits" for the insole, using a four-iron insole and splitting same in two. It is usually considered that three and one-half or four irons is as thin a leather insole as can be employed for welt channeled use. Thus, I can start with stock practically one-half as expensive as normally employed and with stock which will insure greater flexibility in the resultant shoe. The marginal portion of the insole blank from the heel forward may be then coated with adhesive, as shown at 2, and it is feasible to first channel the insole and then apply the reinforcing tape 3, or to first apply the reinforcing tape 3, thus strengthening and thickening the marginal portion of the insole and then channel same.

Preferably the tape 3 is of a width nearly equal to that from the edge of the insole to the line of inner channeled cut, and this tape may be coated or uncoated on either or both sides. Preferably I coat the margin of the insole with adhesive, as shown at 2; then apply the tape 3, which tape is also coated on its under side, thus insuring good adhesion or cohesion with the margin of the insole, and then perform the channel-cutting operation, which would include splitting in a cut 4 from the marginal edge and simultaneously forming the inner channel cut 5. Thereupon the upper surface of the tape 3 is coated with adhesive, as indicated at 6, either after such applying, or pre-coated and thereupon the channel lip-turning operation is performed, folding the tape 3 together as the channeled lips 7 and 8 are forced together, thus forming a sewing rib with the reinforcing tape 3 on the inside, and the channeled lips 7 and 8 on the outside, and all constituting a strong laminated sewing rib of a plurality of layers, with the reinforcing on the inside.

In order to insure the reinforcing tape 3 extending at the base of the sewing rib to insure the inseaming operation to engage the tape, I may indent the between substance 10, viz., between the channel cuts 4 and 5, by pressing or

cutting a groove 12 therein, into which groove the reinforcing tape 3 will be forced when applied to the margin of the insole, as shown in Fig. 5.

I may attach the center of the tape by a line 5 of stitching, as shown at 20, Fig. 3, which stitching would be applied while the tape 3 is flat, and either with the adhesive or without same, this still further insuring the holding of the tape snugly in the base of the groove and strengthening 10 the "between substance."

This may leave the edge of the tape slightly shorter than the channeled lips 7 and 8, as shown at 13 and 14, and when the channeled lip-turning operation is performed the outermost edges of the channeled lips 7 and 8 will be united on top of the tape, as shown in Fig. 6, with the tape 3 completely enclosed. As this top portion is subsequently trimmed after the inseaming operation, it is not necessary to have a wider reinforcing tape applied, the tape sufficiently strengthening the margin of the insole blank even though the tape is slightly spaced from the margins of the channel-cut portions.

My reinforced rib structure with the reinforcing tape on the inside is sufficiently strong for ordinary footwear without gemming, although my improved welt insole can, of course, be gemmed if desired by adding the usual gemmed duck 15 across the entire width of the insole and against the inside of my composite sewing rib. Or a strip reinforcing can be applied, as shown at 16 at the right of Fig. 8.

I claim:

1. A welt insole of the kind described, having a reinforced composite sewing rib formed of a pair of continuous channeled lips cut from the marginal portion of an insole blank, adhesively united with two layers of the reinforcing element, said element being fitted between said continuous channeled lips, and all said four layers being adhesively united into a reinforcing sewing rib, with a portion of the reinforcing element extending substantially to the depth of the line of cut forming said lips.

2. The improved process of making a welt insole with a reinforced sewing rib, which consists in coating the marginal portion of the insole blank with adhesive, forming an indentation parallel with the marginal edge of the blank, and in position to be between the inner and outer channeled lips to be cut therefrom, cutting said lips, adhesively securing a reinforcing tape in said indentation and to both said lips before the lip-turning operation, providing adhesive to the upper surface of said tape, and thereupon turning said lips and attached layers of tape into a composite sewing rib structure with a plurality of layers, having the tape on the inside of the rib constituting four upstanding rib layers adhesively secured together.

ELMER A. ELLIS.
